(57) **CLAIM**

The ornamental design for an anvil, as shown and described.

DESCRIPTION

FIG. 1 is a front perspective view of an anvil, according to a first embodiment.

FIG. 2 is a front view of the anvil, according to the first embodiment.

FIG. 3 is a back view of the anvil, according to the first embodiment.

FIG. 4 is a right-side view of the anvil, according to the first embodiment.

FIG. 5 is a left-side view of the anvil, according to the first embodiment.

FIG. 6 is a top view of the anvil, according to the first embodiment.

FIG. 7 is a bottom view of the anvil, according to the first embodiment.

FIG. 8 is a front perspective view of the anvil, according to a second embodiment wherein the Horn attachment is replaced with a Tapered Mandrel attachment, all other features being identical to the first embodiment.

FIG. 9 a front perspective view of the anvil, according to a fifth embodiment wherein the flat Top Plate attachment is replaced with a convex Top Plate attachment, all other features being identical to the first embodiment.

FIG. 10 is a back view of the anvil, according to the fifth embodiment including the convex Top Plate attachment.

FIG. 11 is a front perspective view of the anvil, according to a sixth embodiment wherein the flat Top Plate attachment is replaced with a concave Top Plate attachment, all other features being identical to the first embodiment; and,

FIG. 12 is a back view of the anvil, according to the sixth embodiment including the concave Top Plate attachment.

The broken lines depict portions of the anvil in which the design is embodied that are not considered part of the claimed design.

1 Claim, 12 Drawing Sheets
